Primary Examiner — Susan Moon Lee(74) *Attorney, Agent, or Firm* — Allen, Dyer, Doppelt, Milbrath and Gilchrist, P.A.(57) **CLAIM**

The ornamental design for a pet bowl assembly, as shown and described.

DESCRIPTION

FIG. 1 is a top perspective view of a pet bowl assembly having a lower part and an upper part;

FIG. 2 is a bottom perspective view of the embodiment shown in FIG. 1;

FIG. 3 is a bottom view of the embodiment shown in FIG. 1;

FIG. 4 is a side view of the embodiment shown in FIG. 1;

FIG. 5 is a top view of the embodiment shown in FIG. 1;

FIG. 6 is an exploded top perspective view of the embodiment shown in FIG. 1;

FIG. 7 is an exploded bottom perspective view of the embodiment shown in FIG. 1;

FIG. 8 is a bottom view of the lower part of the embodiment shown in FIG. 1;

FIG. 9 is a side view of the lower part of the embodiment shown in FIG. 1;

FIG. 10 is a top view of the lower part of the embodiment shown in FIG. 1;

FIG. 11 is a bottom view of an upper part of the embodiment shown in FIG. 1; and,

FIG. 12 is a side view of an upper part of the embodiment shown in FIG. 1.

Broken lines and portions contained within broken lines are not claimed.
